REMOVABLE SECTIONAL COAT LINING

Jack Eilenberg, Brookline, Mass., assignor to
Eleanor Eilenberg, Brookline, Mass.

Application May 1, 1945, Serial No. 591,337

4 Claims. (Cl. 2—97)

1

This invention relates to a removable sectional coat lining or interliner, and more particularly to such an interliner adapted to be utilized with outer garments such as overcoats or the like.

A primary object of this invention is to provide such an improved coat interliner which may be readily attached to and removed from a garment, as desired.

A further and very important object of the invention is the provision of such an interliner which, when not in use within the coat to provide added warmth thereto, may be readily suspended from an interior portion thereof to folded relation in such manner as to be readily accessible for use at all times, and so positioned as to afford a minimum of additional warmth when in carrying position.

Still another object of the invention is the provision of such a construction which may be readily positioned between the body of the overcoat and the inner lining thereof and supported therebetween in such manner as to be substantially invisible when not in use.

A further object of the invention is the provision of such an interliner which may be formed in two parts which may be readily assembled and secured to the garment when desired, to provide substantial warmth and added thickness about those portions of the body where most needed, and which, when disassembled, may be readily folded in such manner as to occupy a relatively small amount of space.

Other objects will in part be obvious and in part be pointed out as the description of the invention proceeds, and shown in the accompanying drawings, wherein there is disclosed a preferred embodiment of this inventive concept.

In the drawings, wherein like reference characters designate like parts throughout the several views:

Figure 1 is a front plan view of an overcoat or similar garment shown in open position and disclosing the interliner of the instant invention in operative position therein.

Figure 2 is a view similar to Figure 1, but showing the interliner removed therefrom and positioned between the inner lining and the body of the garment for carrying.

Figure 3 is a plan view of one of the elements of the sectional interliner.

Figure 4 is a plan view of the other of the elements of the sectional interliner.

Figure 5 is a sectional view taken substantially along the line 5—5 of Figure 2, as viewed in the direction of the arrows.

2

Figure 6 is a fragmentary view of certain constructional details, certain parts thereof being shown as cut away, and disclosing one section of the interliner in folded or carrying position.

5 Figure 7 is a sectional view taken substantially along the line 7—7 of Figure 6.

Having reference now to the drawings, and more particularly to Figures 1 and 2, there is generally indicated at 10 an overcoat including a 10 collar 11, lapels 12, a back portion 13, side portions 14, and oppositely spaced front portions 15 adapted to be secured together when the coat is worn by the conventional buttons and buttonholes. The coat 10 also includes an inner lining 16 and armholes 17 from which extend conventional sleeves (not shown).

A row of spaced buttons 18 extends upwardly along the inner side of the front portion of the coat 10 from a position substantially at the waist 20 line thereof across the top of the side and back portions 14 and 13, and thence downwardly on the inner side of the opposite front portion 15 to the waist. The sections of the interliner of the instant invention are provided with appropriate 25 button holes for engagement with the buttons 18 in order to secure the interliner in position for wear within the garment.

The sectional interliner of the garment is comprised of two sections 20 and 21, each of a configuration adapted to cover the interior of substantially half of the overcoat 10 and each provided with a plurality of spaced buttonholes 22 adapted, when the interliner is to be used, to be engaged by the buttons 18. The meeting sides of the sections 30 20 and 21 are adapted to overlap, and the inner edges of one section, as for example 20, is provided with a row of buttons 23 adapted to engage a row of buttonholes 24 cut in the adjacent edge of the opposite section 21. Each of the sections 35 20 and 21 is provided with an armhole portion 25 and an interior cut-away portion 26 extending from the armhole portion to the lower extremity of the lining, the opposite sides of each section being secured together across the cut-away portion 26, as by means of resilient strips 27, stitched or otherwise suitably secured to the edges of the slit, to provide relative flexibility and ease of movement within the garment when the interliner is in installed position.

40 45 From the foregoing it will now be seen that when the interliner is in the position shown in Figure 1, the warmth and weight of the overcoat 10 in those areas where cold is normally most felt, namely, the back and front of the garment 50 above the waist, is materially increased.

Under milder weather conditions, when it is desired to remove the interliner, it is desirable also to have the same readily available to be utilized in the event of further weather change towards more severe cold. Under such conditions, the sections are removed by unbuttoning the buttons 23 and 18, respectively, and each section is folded longitudinally. The lower portions of the sections 20 and 21 are provided with aligned pairs of buttonholes 30 adapted to register, when the sections are folded in the manner above described and shown in Figure 5. As best shown in Figures 2, 6 and 7, each side of the inner lining 16 is provided at substantially breast height with a transverse slot 31 extending through the inner lining and being located in the side section 14 of the garment, or that portion thereof adjacent the section of the body which is least affected by temperature changes. A reinforcing strip 32 is secured to the body of the coat adjacent and above each of the slots 31 and has secured thereto depending tabs 33 provided with buttons 34 at their extremities, the buttons being positioned in alignment with the buttonholes 30 when the sections are folded as in Figure 5. Thus, it will be seen that when the garment interliner is folded in the manner above indicated, it depends between the body of the coat and the inner lining thereof in proximity to but below the armholes 17 in the position shown in dotted lines in Figure 2, and is supported securely in an out-of-the-way and substantially invisible manner, but is at the same time readily accessible for use in the event that such use becomes necessary.

From the foregoing it will now be seen that there is herein provided an improved removable sectional interliner accomplishing all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In combination, a garment having a body portion, a lining therefor, a removable foldable interliner and means for concealing said interliner during non use including a pocket in said lining, a plurality of fastening means secured within said pocket, a plurality of apertures in said interliner, said apertures arranged to register in aligned groups when said interliner is folded, said fastening means being engageable with said aligned groups of apertures for supporting said

interliner within said pocket in concealed position.

2. In combination, a garment having a body portion, a lining therefor, a removable foldable interliner and means for concealing said interliner during non use including a pocket in said lining, a plurality of fastening means secured within said pocket, a plurality of apertures in said interliner, said apertures arranged to register in aligned groups when said interliner is folded, said fastening means being engageable with said aligned groups of apertures for supporting said interliner within said pocket in concealed position, said plurality of apertures being located adjacent the lower edge of said interliner in its operative position, and at the top when said interliner is inverted for positioning within said pocket.

3. In combination, a garment having a body portion, a lining therefor, a removable foldable interliner and means for concealing said interliner during non use including a pocket in said lining, a plurality of fastening means secured within said pocket, a plurality of apertures in said interliner, said apertures arranged to register in aligned groups when said interliner is folded, said fastening means being engageable with said aligned groups of apertures for supporting said interliner within said pocket in concealed position, said plurality of fastening means being positioned in proximity to and below the arm holes of said garment.

4. In combination, a garment having a body portion, a lining therefor, a removable foldable interliner and means for concealing said interliner during non use including a pocket in said lining, a plurality of fastening means secured within said pocket, a plurality of apertures in said interliner, said apertures arranged to register in aligned groups when said interliner is folded, said fastening means being engageable with said aligned groups of apertures for supporting said interliner within said pocket in concealed position, said garment having a pair of pockets and said interliner comprising a pair of separable sections, each of which is disposable in one of said pockets.

JACK EILENBERG.
